(57) CLAIM

The ornamental design for a strap arrangement, as shown and described.

DESCRIPTION

FIG. 1 is a perspective view of a strap arrangement showing my new design;

FIG. 2 is a front elevational view thereof;

FIG. 3 is a rear elevational view thereof;

FIG. 4 is a right elevational view thereof, the left elevational view being a mirror image; and,

FIG. 5 is a top plan view thereof.

In the drawings, the broken lines are for the purpose of illustrating environment only which forms no part of the claimed design.

1 Claim, 5 Drawing Sheets
